UNITED STATES PATENT OFFICE

JOHAN E. JOHANNESEN, OF BROOKLYN, NEW YORK

DESIGN FOR A SUSPENDERLESS UNIFORM

Application filed March 5, 1931. Serial No. 38,933. Term of patent 14 years.

To all whom it may concern:

Be it known that I, JOHAN E. JOHANNESEN, a citizen of the United States, residing at Brooklyn, in the county of Kings and State of New York, have invented a new, original, and ornamental Design for Suspenderless Uniforms, as shown in the accompanying drawing and described in the following specification.

Figure 1 represents a right side view of a uniform embodying my new design;

Figure 2 represents a front view of the same;

Figure 3 represents a left side view of the uniform;

Figure 4 represents a rear view of the same with the seat flap up.

I claim:

The ornamental design for a suspenderless uniform as shown.

JOHAN E. JOHANNESEN.
